ELECTRIC LIGHTED ILLUMINATING SPHERE
FIXTUREJoseph Levy, Brooklyn, N. Y., assignor to Century
Lighting, Inc., a corporation of New York

Application November 13, 1940, Serial No. 365,404

5 Claims. (Cl. 240—78)

This invention relates to the lighting fixture art and more particularly is directed to an improvement in electrically lighted illuminating fixture construction of compact spherical shape for projecting light in various selective directions.

Among the objects of the invention is to generally improve lighting fixture constructions of the character described comprising few and simple parts that are readily assembled to form a compact attractive appearing structure, which shall be easily adjusted for projecting light beams or rays from a totally concealed light source in a wide range of selective directions, which shall be inexpensive to manufacture, and which shall be practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawing, in which is shown various possible illustrative embodiments of this invention:

Fig. 1 is a front elevational view, shown partially in cross-section to expose the interior structure of an electrically lighted spherical-shaped illuminating fixture constructed to embody the invention;

Fig. 2 is a bottom view of the improved fixture shown in Fig. 1;

Fig. 3 is a fragmentary enlarged view of details of construction of a fixture part shown in Fig. 1; and

Fig. 4 is a front elevational view of the improved fixture showing the same adjusted for projecting light beams or rays in a selective angular direction with respect to the downwardly extending projection as shown in Fig. 1, a portion of the fixture casing being broken away to show the adjusted position of the lamp hanger relative to the fixture casing opening through which the light is projected.

Referring to the drawing, 10 denotes an electrically lighted illuminating fixture construction embodying the invention, which is particularly adapted to be used for show rooms, display windows, photographic lighting and for other similar purposes, permitting changes in a wide range of selective directions of the projected light without requiring the relocating of the fixture from a relatively fixed installation, as for example, as hereinafter described.

As shown in Fig. 1, the fixture 10 is provided with a suitable supporting means 11 which may be rigidly anchored to hang from an outlet box 12 embedded in a ceiling C and covered by a canopy 14, all in the conventional well understood manner. The supporting means 11 may terminate outside of the canopy 14 in a threaded pipe nipple 15 which carries thereon between an exterior upper nut 16 and a pair of interior lock nuts 17, a spherical or globular shell casing 18. There may be interposed a flat friction acting spring washer 19 within the casing 18 under lock nuts 17 to permit ready horizontal rotary adjustment of the casing 18 on the support means 11. By adjusting the lock nuts 17 on nipple 15, the degree of frictional resistance to horizontal rotative movement of the casing 18 may be made to suit any desired requirement. The casing 18 is preferably formed of a suitable sheet material, such as spun or molded metal, and may consist of a hemispherical half 18a which is directly attached for horizontal rotary movement as part of the shell casing 18 to support means 11 as described above. Another hemispherical half 18b, similar to said half 18a, except that it is provided with an opening 18c wherethrough projected light beams or rays pass from a lamp L mounted within the casing 18, is swivelly fitted to said half 18a to complete the shell casing 18. As shown in Figs. 1 and 4 the casing 18 is mounted on the support means 11 so that an axis passing through the latter (indicated by the dot and dash lines X—X) makes an oblique angle α with a plane (indicated by the dot and dash lines Y—Y) passing through the joint between hemispherical halves 18a and 18b, said angle α for general purposes and in the construction shown in the drawing being about 45°.

The lamp L is mounted with its socket receptacle 21 on a right angular shaped swingable hanger 20 which in Fig. 1 is shown to have a horizontally extending arm 20a on which said lamp receptacle 21 is firmly attached. Said arm 20a has its free end united by riveting or welding or other suitable connecting means as at 20b, shown in Fig. 3, to a ring flange 22 which is permanently attached or may be made part of the peripheral edge of the hemispherical half 18b, said ring flange 22 extending wholly within the casing 18 and forming a concealed lap for the butt joint J of the peripheral edges of hemispherical parts 18a and 18b. A vertically extending arm 20c of member 20, as shown in Fig. 1, has its free end united by suitable connecting means as at 20d to ring flange 22 on the dia-

metrically opposite portion thereof to connecting means 20b in the manner similar to that described above.

The member 20 may also be provided with a center or mid portion 20e between arms 20a and 20c shaped to cooperate with a bracket 23 secured to the interior surface of the hemispherical half 18a within the casing 18 adapted to provide with an intermediate screw clamp interconnecting means 24, a swivel attachment for the hanger 20 with the receptacle 21, lamp L and hemispherical part 18b with hemispherical part 18a. The axis about which said swivel attachment is effective is indicated by dot and dash lines Z—Z in Figs. 1 and 4, which makes an oblique angle β with axis X—X passing through the supporting means 11, said angle β for general purposes also being about 45° as shown in the drawing. The screw interconnecting means 24 may comprise the bolt 24a securely fastened to the bracket 23 by means of a lock nut 24b or other suitable anchorage, and wing nut 24c with a coil compression spring 24d interposed between the hanger mid-portion 20e and the wing nut 24c as shown in Fig. 1.

The receptacle 21 in which the lamp L is mounted may be connected to a suitable power source (not shown) through conductor wires 25 which pass through the pipe nipple 15 and include the slack portion 25a to permit relative movement of the receptacle 21 with the hanger 20 with respect to the supporting means 11 as hereinafter described.

The lamp L preferably is of the reflecting type, having reflector sides R and a diffuser, color screen or lens end E, the casing opening 18c being made of equal to or slightly larger than the diameter of the lamp diffusing end E as shown in Fig. 1. By using the reflector type of lamp L with the diffusing end E, the construction of lighting fixture 10 may be simplified to eliminate the necessity of providing desirable light reflecting and diffusing means as part of the fixture 10.

With parts constructed as described above and shown in the drawing, the practical utility of the lighting fixture 10 will now be evident. To assemble the parts of fixture 10, hemispherical casing part 18a is first secured in place on supporting means 11 as shown in Fig. 1, without the hemispherical casing part 18b. The conductor wires 25 are next connected in circuit with the lamp receptacle 21 in the well known manner. Then the hemispherical casing part 18b is mounted in assembled position by swivelly attaching hanger mid-portion 20e to bracket 23 by means of the interconnecting means 24, as shown in Fig. 1. Lastly, the lamp L is mounted in place in receptacle 21. When the electric power is applied to conductor wires 25, light beams or rays are projected from the lamp L concealed within the casing 18 through opening 18c.

To change the direction of the light rays projected from fixture 10 through opening 18c, the hemispherical casing part 18b is simply rotated about the axis Z—Z with respect to casing part 18a to move the opening 18c in the direction the light rays are desired, as for example, moved from the position shown in Fig. 1 to that shown in Fig. 4. The movement of the casing part 18b carries with it the hanger 20, receptacle 21, and lamp L, and swings on the screw interconnection clamp 24. Frictional tension against movement and the retension of the assembly of the hemispherical parts 18a and 18b exerted by said interconnection 24, may be adjusted by screwing the

wing nut 24c on the bolt 24a, which increases or decreases the effectiveness of the spring 24d. A still wider range for varying the direction of the projected rays from the fixture 10 is provided by horizontally rotating the casing 18 on its swivelling mounting on support 11 as well as giving the hemispherical casing part 18b swivelling movement with respect to hemispherical part 18a.

It will be noted that in all changes of directing the projecting rays, the lamp L always turns with the casing opening 18c so that the diffusing end E and reflecting sides R of said lamp L are positioned for the initial maximum desired effectiveness. As seen from Fig. 1, a swivelling movement of 360° is permitted the shell casing 18 with respect to supporting means 11, while a relative swivelling movement of 180° between hemispherical casing part 18b with respect to part 18a is sufficient for practical purposes, an abutment stop 26 being provided to extend from the interior surface of the casing 18 to coact with the hanger arm 20c to limit the relative movement between said parts 18a and 18b.

It will thus be seen that a lighting fixture construction is provided in which the several objects of the invention are achieved and which is well adapted to meet the conditions of practical use in an efficient manner.

As various embodiments might be made of the above invention and as various changes might be made in the embodiments above set forth, it is to be understood that all matters herein set forth or shown in the accompanying drawing are to be interpreted as illustrative and not in a limiting sense.

Having thus described my invention, I claim as new and desire to secure by Letters Patent:

1. In a lighting fixture construction of the character described, an electric light source, a spherical shell casing for housing said light source comprising upper and lower substantially hemispherical parts, said lower part having an opening from which light beams from said source are projected, swivel means interconnecting with said upper part whereby the casing may be rotatably mounted from a relatively rigid support, means for supporting the light source carried by said lower part, interconnecting means within the casing for attaching said lower part through the supporting means with the upper part to movably secure said parts in assembly whereby the lower part with the opening may be positioned with respect to the upper part to selectively direct the projected light beams from said opening in various angular directions, said light source being retained in a relatively fixed position with respect to said opening when directing the light beams in all selective various directions, the plane of the periphery of said parts being located at an oblique angle with respect to the axis passing through said swivel means and rigid support.

2. In the lighting fixture construction defined in claim 1, in which said swivel means and interconnecting means each include frictional adjustment means for regulating the resistance of the movements of said casing part having the opening with respect to the other casing part, and of said other part with respect to the swivel means.

3. In a lighting fixture construction of the character described, an electric light source, a spherical shell casing for housing said light source comprising two substantially hemispherical parts, one of said parts having an opening through which light rays from said source are projected, swivel means connecting with the other

of said parts whereby the casing may be rotatably mounted from a relatively rigid support, interconnecting means within the casing movably securing said parts in assembly whereby the part with said opening may be positioned with respect to the other part to selectively direct the projected light rays from the opening in various angular directions, the plane of peripheries of said parts being located at an oblique angle with respect to an axis passing through said swivel means and rigid support, a portion of said interconnecting means movable with the part having said opening serving as a support for said light source whereby the latter is retained in a relatively fixed position with respect to said opening when directing the light rays in all selective various directions, said hemispherical parts being assembled with a butt joint to provide a smooth exterior surface for the spherical shell casing, and a ring flange extending along the interior surface of one of said parts forming a concealed lap for the butt joint.

4. In a lighting fixture construction of the character described, an electric light source, a spherical shell casing for housing said light source comprising two substantially hemispherical parts, one of said parts having an opening through which light rays from said source are projected, swivel means connecting with the other of said parts whereby the casing may be rotatably mounted from a relatively rigid support, interconnecting means within the casing movably securing said parts in assembly whereby the part with said opening may be positioned with respect to the other part to selectively direct the projected light rays from the opening in various angular directions, the plane of peripheries of said parts being located at an oblique angle with re-

spect to an axis passing through said swivel means and rigid support, a portion of said interconnecting means movable with the part having said opening serving as a support for said light source whereby the latter is retained in a relatively fixed position with respect to said opening when directing the light rays in all selective various directions, said hemispherical parts being assembled with a butt joint to provide a smooth exterior surface for the spherical shell casing, a ring flange extending along the interior surface of the part with said opening forming a concealed lap for the butt joint, said portion of the interconnecting means forming a hanger rigidly secured to the ring flange.

5. In combination with an electric lamp having reflector sides and a light modifying end, of a lighting fixture comprising a metallic two-part spherical shell casing for housing said lamp, one of said parts being of hemispherical shape and formed with an opening through which light rays from said lamp end are projected, the other of said parts being of hemispherical shape and swivelly secured to a relatively rigid support, interconnecting means within the casing securing the parts in movable assembly whereby said part with the opening may be positioned with respect to the other part to selectively direct the rays from said lamp end through the opening in various angular directions, said interconnecting means including a hanger secured to move with the casing part having said opening and swivelly supported from the interior side of the other casing part, said hanger serving as a mounting means for retaining the position of the lamp end relatively fixed with respect to said opening.

JOSEPH LEVY.
